PROTECTIVE FOOT GUARD

Norman C. Holtkamp, Playa Del Rey, and Jules J. Oppenheim, Los Angeles, Calif.

Application February 6, 1956, Serial No. 563,476

1 Claim. (Cl. 36—72)

This invention relates to a foot protective guard and particularly to a foot protective guard which may be attached to a conventional shoe to protect a toe or toes which have been surgically or otherwise treated.

Chiropodists, or physicians or surgeons, after treating surgical or non-surgical conditions of the toes or injuries to the toes resulting from accidents, find it desirable to protect the toe or toes from contact with objects in order to avoid any pressure on the treated portion, which pressure might cause pain or further injury to the treated toe. The chiropodist, or physician or surgeon after treatment of the toes, may permit the patient to be mobile but desires to avoid any complications which might result from an object being dropped on the portion of the toe which has been treated or by reason of the patient accidentally bumping or kicking against objects which might damage the treated portion of the foot. To eliminate pressure upon the critical portion of the foot, it is standard operating procedure for the chiropodist, or physician or surgeon, to cut away that portion of a patient's shoe which covers the treated portion and advise the patient to avoid contact of the treated portion of the foot with any object which might tend to injure it. Sometimes the chiropodist, or physician or surgeon, places a cast or splint upon the foot for protective reasons.

The general object of the invention is to provide a foot protective guard which has the constructional elements so arranged and disposed that when attached to the sole of a shoe it is disposed over and above the foot so that the toe or toes are protected from injury if an object is dropped on the foot or when the shoe accidentally bumps or is kicked against an object which might otherwise damage or exert pressure against the foot.

A further object of the invention is to provide a foot protective guard which is readily and quickly attached to and detached from a conventional shoe.

A further object of the invention is to provide a foot protective guard which may be worn by a patient whose foot has been surgically or non-surgically treated, particularly the toe or toes, over a shoe which has a cut-out portion over the treated portion which will not interfere with the walking of the patient nor impair the flexibility of the shoe.

Another object of the invention is to provide a protective foot guard which will be reliably and effectively retained in proper protective position on the shoe of the wearer during walking.

A still further object of the invention is to provide a foot protective guard which is light in weight, simple and inexpensive to manufacture and is of unitary construction.

A further object of the invention is to provide a foot protective guard which may be used to protect a portion of a patient's foot.

A still further object of the invention is to provide

2

a foot protective guard which may be used to protect all of the toes on a patient's foot.

In the accompanying drawings, we have illustrated, by way of example, but not by way of limitation, a 5 specific embodiment of our invention. In such drawings, Fig. 1 is a perspective view of the guard on a shoe to protect the fifth digit; Fig. 2 is a perspective view of the front portion of a shoe with the guard in place to be positioned on the shoe; Fig. 3 is a fragmentary 10 detail view showing the eyelet or loop portion of the guard with a shoestring positioned within the eyelet or loop to removably secure the guard to the shoe; Fig. 4 is a fragmentary detail view, partly in cross-section, of the end portion of a rod member or pin having barbs thereon positioned within an opening in the sole of a shoe; Fig. 5 is a top plan view of the guard on a shoe of a shape to fit over the entire fore part of a shoe to protect all of the toes; and Fig. 6 is a perspective view of the front portion of the shoe shown in Fig. 5 with the guard 15 in place to be positioned on the shoe.

Referring more particularly to the drawings, in which similar reference characters identify similar parts in the several views, 10 designates a shoe which has had a portion of the fore part of the shoe cut over the fifth 20 digit leaving an opening. The protective foot guard is designated generally as 11. The protective foot guard 11, in the embodiment shown in Figs. 1 through 4, is designed to protect the fifth digit of a patient, whose toe has been surgically or otherwise treated. The protective 25 toe guard 11 is constructed by forming, shaping and securing together, such as by welding, a number of rod or bar elements. Rods, such as bronze, steel, plastic, or any suitable resilient material of sufficient strength may be used to form the protective foot guard 11. To construct the embodiment illustrated in Figs. 1 and 2, an arched rod 12 is shaped substantially parallel to and conforming to the shape of the sole 13 of the shoe 10. Rigidly secured, such as by welding, to the arched rod 12 is a second rod 14 arched upwardly and rearwardly 30 and rigidly secured, such as by welding, to an eyelet or loop 15. The eyelet or loop 15 may be formed of the same material as the rods or the rod 14 may be looped to form the eyelet 15. Adjacent the other end of the arched rod 12 is rigidly secured, such as by welding, a third arched rod 16, which is arched upwardly and rigidly secured, such as by welding, to the eyelet or loop 15. If desired the eyelet 15 may be formed by looping the rod 16. The lower extremity of the second rod 14 is bent inwardly to form the retaining pin 17. The lower 35 extremity of the third rod 16 is bent inwardly to form the retaining pin 18. The arched rod 12, the second rod 14 and the third rod 16 form a framework within which are rigidly secured, such as by welding, a plurality of arched rods 19, forming a latticework. The arched rods 19 are shaped to conform to the portion of the fore part of the shoe 10 over which the protective guard 11 is 40 adapted to be worn.

The retaining pins 17 and 18 are adapted to fit into openings 20 and 21, respectively, which are holes of suitable length drilled or otherwise formed into the sole 13 of the shoe 10. We prefer to have the holes approximately one-and-one-quarter inches in depth. The eyelet or loop 15 is adapted to have the shoe lace 22 tied thereto, as shown most clearly in detail in Fig. 3.

We have discovered that the protective foot guard or shield 11 shown in Figs. 1 and 2 will remain effectively 45 place during ordinary ambulatory activity of a patient when the retaining pins 17 and 18 are fitted into the openings 20 and 21 of the sole 13 of the shoe 10 and the shoe lace 22 is tied to the eyelet or loop 15, without the necessity of any locking device. This is due to the resilient character of the materials used, the depth of the 50

holes 20 and 21, and the length of the retaining pins 17 and 18 of at least the length equal to the depth of the openings 20 and 21. However, if it is desired to secure the protective foot guard 11 more or less permanently to the shoe 10, we may provide barbs 23 on the retaining pins or prongs 17 and 18 to more rigidly retain the retaining pins 17 and 18 in the openings 20 and 21, respectively of the sole 13 of the shoe 10. This is shown in Fig. 4 in which the barbs 23, after insertion of the pin 17 in the opening 20, dig into the material of the sole 13 preventing dislodgment of the protective guard, even when subject to relatively strong dislodging force. If desired, we may glue the retaining pins 17 and 18 in place within the openings 20 and 21.

In Figs. 5 and 6, we have shown another embodiment of our invention in which 10 designates a shoe which has had the entire toe covering portion of the shoe cut out therefrom. Such a cut-out may be required in cases where the chiropodist, or physician or surgeon desires that all possible pressure from the shoe on the toes be removed. The protective guard, designated generally as 11, illustrated in Figs. 5 and 6, is adapted to cover the entire toe portion of the shoe and is constructed of rod elements similar to the embodiment described in Figs. 1 through 4. To form the embodiment shown in Figs. 5 and 6 a resilient rod or bar 24 is arched transversely of the sole 13 of the shoe 10. Rigidly secured, such as by welding, to the transverse rod 24 and normal thereto is a second rod 25 shaped substantially parallel to and conforming to the shape of the left side of the sole 13 of the shoe 10. A third rod 26 is rigidly secured, such as by welding, to the transverse rod 24 and normal thereto, the rod 26 being shaped substantially parallel to and conforming to the shape of, the right side of the sole 13 of the shoe 10. The rods 25 and 26 converge at the anterior or tip portion of the sole 13 of the shoe 10 at 27 where the said rods are rigidly secured together, such as by welding. If desired a single rod may be shaped to form the elements 25 and 26. A plurality of arched rods 28 are then secured in spaced relationship by welding to said transversely arched rod 24, the rods 28 converging forwardly to the anterior or tip portion of the shoe 10 at 27, where they are rigidly secured together, such as by welding.

To secure the protective guard 11 to the shoe in spaced relationship above the cut-out portion of the shoe 10, the rod 24 has its two lower extremities bent inwardly to form the retaining pins 29 and 30. The retaining pins 29 and 30 are adapted to fit into openings 31 and 32 respectively, which are holes of suitable length, such as approximately one and one-quarter inches in depth, drilled or otherwise made into the sole 13 of the shoe 10. At the anterior portion or tip of the shoe 10, at 27, one of the rods 25, 26 or 28, may be bent inwardly to form a pin 33. If desired the pin 33 may be a separate rod member welded to the material formed by the juncture of the rods at 27. The pin 33 is adapted to fit into the opening 34, which is a hole of suitable length, such as approximately one and one-quarter inch in depth, drilled or otherwise formed by an awl or similar tool into the sole 13 of the shoe 10.

The protective guard 11, shown in Figs. 5 and 6, being made of resilient rod material, is easily positioned on the shoe 10 by spreading open the posterior portion of the guard 11, as shown in dotted lines in Fig. 6, inserting the pin 33 into the opening 34 and allowing the retaining pins 29 and 30 to be snapped into the respective openings 31 and 32. We have discovered that this toe protective guard 11 will remain effectively in place, but we may provide barbs on the retaining pins 29, 30 and 33 to more rigidly retain the said pins in the openings 31, 32 and 34, respectively. If desired the pins 29, 30 and 33 may be glued in place within the holes 31, 32 and 34, respectively.

The described protective guard, constructed in accordance with my invention, may be formed to protect any

of the digits of the foot. Thus, while Figs. 1 through 4 show our invention to protect the fifth digit, a similar construction may be used, for example, to protect the first digit by reversing the shaping of the embodiment shown in Figs. 1 through 4.

It will be apparent from the above description that we have provided a novel protective foot guard whereby the foot of the wearer of a shoe is protected from the impact of an object dropped upon the protective device or against 10 which the protective device may be bumped. The resilient material of which the rods are formed may be constructed of suitable material, sufficiently firm to withstand impact. While we have described rod material, heavy wire may be used of sufficient resiliency and strength. If desired 15 the rods or wire may be interwoven to form an appropriate latticework. The protective guard constructed in accordance with my invention is light and is suitable to be fitted to all types of shoes. An added advantage of the protective guard as before described is that free circulation of 20 air is permitted not only because the protective guard is positioned and spaced above the fore part of the shoe but also because of the latticework or barred construction.

As shown most clearly in Figs. 1 and 5, our protective foot guard, when attached to a shoe, is positioned over 25 and above the portion of the shoe to be protected, by the pins. If, for example, an object is dropped upon the protective guard, the force of the impact is absorbed by the resilient material of which the guard is formed and the force is transmitted through the retaining pins to the 30 sole of the shoe, thus avoiding any pressure upon the foot. The same result occurs when the foot is bumped against an object due to the fact that my protective guard is spaced above the fore part of the shoe and supported by the retaining pins positioned within the openings in the 35 sole of the shoe.

We have described our foot guard or shield in connection with shoes which have cut-out portions. It will be understood that our invention may be used with shoes that have not been so cut out. For example, our invention 40 may be utilized as a protective foot guard for use by workers in industrial establishments or factories where there is danger of heavy objects falling upon the foot of a worker, i. e., our invention may be used to convert an ordinary street shoe into a safety shoe. Our invention, 45 consisting of a foot protective guard light in weight is easily secured to an ordinary shoe and will serve to protect that portion of the foot which is most likely to be injured by falling objects, namely the toes. The spaced relationship of my foot protective guard above the fore part of 50 the shoe will withstand impact from heavy objects and transmit the pressure from falling heavy objects to the sole, rather than to the base of the toes as is the case with safety shoe constructions currently in use. The protective foot guard for such industrial use, where it is 55 desired to use the guard on the same shoes as the worker uses for street wear, would not be provided with barbs. Thus the wearer may use his ordinary street shoes, the only operation necessary to utilize my protective guard being the drilling or otherwise making of the necessary 60 holes in the soles of the shoes. Thus our inventive device may be easily and quickly attached when the worker desires to use the protective foot guard and easily and quickly removed from the shoe after the work in the factory has been completed.

65 While we have described a particular embodiment of our inventive structure, it is obvious that many changes may be made without departing from the spirit of our invention.

We claim:

70 A foot protective guard extending in spaced relationship over and above the fore part of a shoe and comprising a shaped latticework shield composed of rod material having the general form of the top of the fore part of the shoe and a plurality of integral inwardly extending rod members on the lower edge of said latticework shield

at the front and side thereof and adapted to fit into openings provided therefor in the sole of said shoe to detachably retain said guard on the shoe.
